FIG. 3.

INVENTOR

UNITED STATES PATENT OFFICE

171,950

COMBINED TEETHING RING AND RATTLE OR SIMILAR ARTICLE

David Pelton Moore, Glen Oaks, N. Y.

Application May 1, 1953, Serial No. 24,795

Term of patent 14 years

(Cl. D34—15)

To all whom it may concern:

Be it known that I, David Pelton Moore, a citizen of the United States, residing at Glen Oaks, in the county of Queens and State of New York, have invented a new, original, and ornamental Design for a Combined Teething Ring and Rattle or Similar Article, of which the following is a specification, reference being had to the accompanying drawing, forming a part thereof, and in which:

Figure 1 is a top plan view of a combined teething ring and rattle or similar article, showing my new design.

Figure 2 is a side elevational view thereof; and Figure 3 is a perspective view thereof.

The drawing is stippled to indicate color contrast, and portions thereof are diagonally lined to indicate transparency.

I claim:

The ornamental design for a combined teething ring and rattle or similar article, as shown and described.
